INJECTION APPARATUS

Edwin A. May, Ridgewood, N. J., assignor to
Becton Dickinson and Company, Rutherford,
N. J., a corporation of New Jersey

Application September 29, 1949, Serial No. 118,701

7 Claims. (Cl. 128—173)

1

This invention relates to an improved injection apparatus primarily intended for the expulsion of medicament at skin penetrating velocities such that it will be unnecessary to employ a hypodermic epidermis-penetrating needle as has heretofore been employed.

It is a primary object to furnish a hypodermic apparatus of the velocity injection type which may be employed in connection with intradermal or allergy techniques and for intramuscular injections; such apparatus being capable of ready loading and use by an operator with the expenditure of a minimum amount of time and effort.

A further object is that of furnishing an assembly of this type which will embody relatively few parts, each individually simple and rugged in construction; such parts being capable of production in large quantities at comparatively small expense and the apparatus moreover being primarily intended to operate without it being necessary to incorporate in the same a power motor mechanism to effect the desired expulsion of the medicament.

With these and other objects in mind reference is had to the attached sheet of drawings illustrating practical embodiments of the invention and in which:

Fig. 1 is a sectional side view of one form of the unit;

Fig. 2 is an enlarged transverse sectional view taken along the lines 2—2 and in the direction of the arrows as indicated in Fig. 1;

Fig. 3 is a view similar to Fig. 1 but showing the parts in a different position;

Fig. 4 is a fragmentary detail of a portion of the assembly showing the same in enlarged scale; and

Fig. 5 is a sectional side view of an alternative form of apparatus.

Primarily referring to Figs. 1 to 4, the numeral 10 indicates an outer holding or manipulating member which is hollow and may be of circular outline. At one end this tube mounts a plug 11 which may present at its outer end a skin-contacting flange or element 12. This plug also 40 mounts a nozzle 13 having a reduced outlet bore 14. Adjacent the inner end of plug 11 there is disposed within the member 10 a supporting or stop member 15. Between this member and plug 11 a cushion in the form of a rubber disk 16 may be interposed.

Member 15 is bored and there preferably extends through the same a cylinder 17 which is of relatively great length and small diameter. This cylinder may be secured to plug 11 by a body

10 of solder as at 18. A washer 19 is conveniently interposed between the end of the cylinder and nozzle 13. Within cylinder 17 a rod 20 is slidably mounted to function as a piston. The length of this rod is such that when fully projected it extends substantially throughout the entire length of the cylinder and has its rear end projecting beyond member 10. To that rear end a knob 21 functioning as a thumb or palm rest is secured.

15 To guide the movements of the piston and to stabilize the same a sleeve 22 may be secured to the actuator 21. The opposite end of sleeve 22 has attached to it the member 15. Thus, it is apparent that as the actuator or knob is shifted to reciprocate piston 20 a guiding action will be established between the inner face of member 10 and the outer face of sleeve 22 as well as between the outer face of cylinder 17 and the bore of member 15. The latter assembly will establish proper support adjacent the inner end of the apparatus. A corresponding support adjacent the outer end of the apparatus is conveniently furnished by securing to the rear end of cylinder 17 a threaded collar 23 which mounts a correspondingly threaded cap or sleeve 24; these parts being adjustable by virtue of their threaded engagement. A sealing element 25 may be disposed within the cap and slidably contact the face of rod 20 to thus furnish a seal for the latter. The outer face of cap 24 may be formed with one or more grooves 26 to provide by-passes for air which would otherwise be entrapped. Adjustment of the seal or packing 25 may conveniently be obtained by forming both member 10 and sleeve 22 with aligned openings 27. An opening 28 may also be formed in cap 24 as shown in Fig. 1. Accordingly if the parts are disassembled to some extent a suitable implement may be introduced through openings 27 and 28 to retain the cap against rotation. Thereupon by turning plug 11 and cylinder 17 with respect to member 10, collar 23 may be projected or retracted with respect to cap 24 to obtain the desired adjustment of seal 25.

45 Thus, in the structure shown in Figs. 1 to 4, an assembly is furnished which involves a medicament-receiving cylinder and a piston for expelling medicament therefrom. This cylinder may be filled with medicament (after desired sterilization of the parts) by immersing the outer end of the unit in medicament and retracting the piston. Under these circumstances nozzle 13 may, or may not, be removed according to the convenience of the user. In any event a substantially permanent assembly is furnished the

detailed operation of which will be hereinafter described.

Under certain conditions, it may be desirable to furnish an apparatus of this design in which the medicament will be contained in a pre-filled ampule which, after operation of the parts, may be discarded. Such an apparatus has been shown in Fig. 5 in which the numeral 29 indicates the knob or actuator attached to the rear end of rod 30 and which also mounts a guiding sleeve or element 31 slidably bearing against the inner face of the holding member or tube 32. The outer end of member 32 mounts a plug 33 presenting a contact or bearing surface 34 and supports a nozzle 35 formed with a discharge orifice 36. These parts thus generally correspond to the parts heretofore described in connection with Figs. 1 to 4.

However, in lieu of the cylinder 17 an ampule or cartridge 37 is employed into which the rod 30 may be projected. The interior of this cartridge contains liquid medicament. Its rear end is closed by a piston stopper 38. Its forward end may be closed by a rupturable or frangible seal 39. The inner end of nozzle 35 is preferably pointed so as to effect the rupture of seal 39 as the parts are fully seated. To support the ampule or cartridge a tube 40 may be provided which receives the same; the clearance between these parts having, for the purposes of illustration, been somewhat exaggerated. In common with the structure shown in the preceding figures a cushioning unit 41 may be provided adjacent the inner face of plug 33.

Sleeve 31 mounts adjacent its inner end a stop unit 42 which limits retraction of the sleeve and the parts associated therewith. Such limiting or stopping action may occur incident to engagement of the unit 42 with a collar 43 encircling tube 40 adjacent its inner end and fixed against movement with respect to the same. This collar may have outer threads mounting the cap 44 which, in common with the previous structure contains a seal 45 slidably engaging the rod 30. The end of cap 44 may terminate in a nut portion so that the seal may be adjusted or tensioned as desired. In advance of this seal a stop element 46 is disposed which bears against the rear end of the ampule 37 to limit movement of the latter.

In an apparatus of this type it is apparent that plug 33 may be dismounted. Thereafter an ampule or cartridge 37 may be disposed within the bore of tube 40; it being understood that the actuator 29 and its associated parts should be fully retracted during this loading operation. When now plug 33 is seated the pointed inner end of nozzle 35 will penetrate seal 39 to establish communication between the interior of the ampule and the bore of the nozzle. The parts may be so proportioned that during the final seating operation of the plug the bore of the nozzle is completely filled with medicament. Under these circumstances actuator 29 may be projected to expel the medicament. Thereupon plug 33 may be dismounted and the spent ampule may be withdrawn and discarded. Upon the rod 30 again being retracted a new ampule may be projected until it engages stop 46 and the entire cycle may be repeated. In common with the cap 24 of Figs. 1 to 4 a groove 47 may be formed in cap 44 to permit a by-passing of the air as the parts are reciprocated.

In both forms of apparatus it is preferred to employ a cannula to provide tubes such as

17, 37 and 40. The clearance between tube 17 and rod 20 should not be over .001". Such a fit may be readily obtained by, for example, rubbing the piston with emery cloth or other suitable material. The orifices 14 and 36 may be from .004" to .008" in diameter. Where desired they may incorporate lesser or greater diameters. The piston-ampule clearance should also preferably not be in excess of .001". Conveniently the holding members 18 and 32 may be formed of $\frac{1}{2}$ " stock. For ordinary purposes the over all length of the unit may be from six to seven inches. This again may be varied as heretofore pointed out.

15 The following table will generally outline the characteristics of the apparatus. The first line defines in inches plunger diameter and the second line plunger area in square inches. The third line shows the pressures per square inch developed in response to the exertion of a 10 pound thrust. The fourth line shows the stroke in inches necessary in a $\frac{1}{4}$ cc. unit while the fifth line shows such stroke in connection with a $\frac{1}{16}$ cc. apparatus. The sixth line defines the gauge of the cannula which should be employed in the different forms to provide the desired result. Thus:

	.042	.046	.054	.062	.071	.085
.00139	.00173	.00229	.00307	.00395	.00566	
7.200	5.800	4.360	3.250	2.540	1.770	
11.00	8.82	6.66	4.98	3.86	2.70	
4.38	3.52	2.67	1.99	1.55	1.08	
17	16	15	14	13	12	

35 As is obvious it is desirable that the instrument should not exceed a certain over all length in that its handling and manipulation becomes awkward beyond that length. Under ordinary dimensions no difficulty will be experienced in having the capacity of the instrument around $\frac{1}{4}$ cc. 40 If a larger dosage of medicament is to be administered to the patient, then multiple injections may be resorted to. An instrument having a capacity of around $\frac{1}{16}$ cc. may be used, for example, for allergy work where a dose of that amount is to be administered. As is obvious the instrument may have greater or smaller capacities than those mentioned. In a $\frac{1}{4}$ cc. instrument where the plunger diameter is, for example, .054" or .062", pressures of 4360 pounds per square inch and 3250 pounds per square inch respectively are achieved with a 10 pound thrust being exerted on the actuator. The corresponding strokes in such instruments would be 6.66" 45 and 4.98" respectively (no allowance for over-load being included).

50 In intradermal or allergy work, it is presently proposed to employ minimum pressures of 2000 pounds per square inch. In intramuscular injections it is proposed to employ not less than 3000 pounds per square inch. The injection orifice would preferably be on the order of from .004" to .008". If larger orifices are employed then it is highly desirable to utilize an instrument having a long stroke. In this connection it will be understood that with a small orifice a consequently restricted flow will result and the hand is capable of maintaining a relatively constant force on the piston assembly; therefore the stroke is not limited in that case.

55 In both forms of apparatus it will be appreciated that the assembly is initially loaded with medicament. In the structure of Figs. 1 to 4 after such loading has been resorted to the plunger may be slightly projected so that any air within the

cylinder will be discharged. In the structure of Fig. 5 the elimination of any entrapped air may occur as the nozzle assembly is finally positioned. In both cases the nozzle may extend beyond the supporting flange to a lesser extent than has been illustrated, in which case the supporting parts 12 and 34 will cooperate with the skin surface to prevent lateral displacement. Of course the discharge end of the nozzle may be spaced from the skin although this is not desirable. In any event, with the projection of the piston by exerting thrust against the actuator the desired pressures will be created and the medicament will be injected through the epidermis without having to employ a skin-piercing needle.

Thus, among others, the several objects of the invention as specifically aforesaid are achieved. Obviously numerous changes in construction and rearrangement of the parts might be resorted to without departing from the spirit of the invention as defined by the claims.

I claim:

1. An injection apparatus comprising an exterior supporting member, an actuator, a piston rod secured to said actuator and projectible into said member, a tube also secured to said actuator to be movable therewith, said tube slidably engaging the interior of said member to assist in guiding the movement of the rod within the latter, an assembly fixed with respect to said member and slidably engaging said rod, said assembly being formed with an air by-pass whereby air may flow from one to the other side of said assembly within said tube.

2. A hypodermic injection apparatus including in combination a member to be grasped, means providing a medicament chamber, said chamber and member each comprising elements tubular in section and said member being concentrically disposed and spaced with respect to the outer wall defining said chamber, a tube having its inner end projectible into said space and slidably bearing against the inner face of said member, an actuator member mounted by the outer tube end at a point beyond said member and a rod connected to said actuator and projectible through said chamber to expel medicament therefrom.

3. A hypodermic injection apparatus including in combination a member to be grasped, means providing a medicament chamber, said chamber and member each comprising elements tubular in section and said member being concentrically disposed and spaced with respect to the outer wall defining said chamber, a tube having its inner end projectible into said space and slidably bearing against the inner face of said member, an actuator member mounted by the outer tube end at a point beyond said member, a rod connected to said actuator and projectible through said chamber to expel medicament therefrom, the inner face of said tube being spaced from the outer face of the element defining said chamber and means carried by said tube and slidably bearing against the outer face of said element to guide the parts.

4. A hypodermic injection device including in combination an actuating knob, a sleeve, a piston rod, both said rod and sleeve being secured against movement with respect to said knob, said sleeve encircling and being spaced from said rod,

an outer tubular member encircling said sleeve and slidably supporting the same, a tube defining a medicament-receiving chamber secured against movement with respect to said outer member and disposed within the same, a supporting collar carried by said tube towards that end which is adjacent said knob, a stop member fixedly carried by said sleeve adjacent its opposite end, said stop member slidably encircling said tube and being engageable with said supporting collar when said knob is moved away from said outer member and said rod being projectible through said tube and being slidably supported by said collar.

5. A hypodermic injection device including in combination an actuating knob, a sleeve, a piston rod, both said rod and sleeve being secured against movement with respect to said knob, said sleeve encircling and being spaced from said rod, an outer tubular member encircling said sleeve and slidably supporting the same, a tube defining a medicament-receiving chamber secured against movement with respect to said outer member and disposed within the same, a supporting collar carried by said tube towards that end which is adjacent such knob, a stop member fixedly carried by said sleeve adjacent its opposite end, said stop member slidably encircling said tube and being engageable with said supporting collar when said knob is moved away from said outer member, a seal associated with said collar, means cooperable with said collar and seal to constrict the latter and said rod being projectible through said tube and having slidably engagement with said seal.

35 6. An injection device as specified in claim 4 in which said tube comprises an ampule having a great length relative to its diameter, the rod is of a substantially equal length and the actuator knob constitutes the sole projection means for said rod, a nozzle through which medicament is discharged and means for supporting said nozzle with respect to said device at a point opposite that at which said knob is disposed.

7. A hypodermic injection device as specified in claim 6 in which said nozzle includes an outer end extending away from said knob and an inner end extending towards said ampule, said inner end providing a rupturing surface for engagement with a seal associated with said ampule.

EDWIN A. MAY.
